ELECTRIC FURNACE AND PROCESS OF HEATING SUBSTANCES.

1,094,354.

Specification of Letters Patent.

Patented Apr. 21, 1914.

Application filed October 28, 1896. Serial No. 610,285.

To all whom it may concern:

Be it known that I, ERWIN F. VON WILMOWSKY, a citizen of the United States of America, residing at the city of Boston, 5 Commonwealth of Massachusetts, have invented certain new and useful Improvements in Electric Furnaces and Processes of Heating Substances Uniformly and at a Controllable Temperature in Electric Arcs, 10 and that the following is a description of the invention which will enable those skilled in the art to which it appertains to make and use the same, reference being had to the different figures of the accompanying drawings, in which the same letters designate 15 identical or analogous parts.

My invention relates to electric furnaces and processes of heating substances, in which the electric arc is formed and utilized 20 for the purpose of heating, and the principal object of the invention is to regulate the position of the arc at will and control its movements to insure equal and thorough heating and equal wear of the furnace parts. 25 Heretofore apparatus of this class has been so constructed that the electrical discharge or arc has been located, and hence an intense effect has resulted adjacent thereto with but little heat at other portions of the 30 furnace. With such apparatus rapid destruction of the heating chamber ensues, and it is difficult to act on a charge of material in a uniform manner.

In carrying my invention into effect I 35 provide a heating chamber in which an arc is established and maintained between adjacent electrodes, the said electrodes being parallel to each other, and the arc is caused to change its position along the length of 40 said electrode in order to heat the entire heating chamber.

In the embodiment of my invention illustrated, and which I shall describe, one of the electrodes is a hollow cylinder, of carbon, 45 which constitutes the heating chamber of the furnace. The other electrode is a carbon rod extending through said cylinder. The arcing surfaces of these electrodes may be concentric cylindrical surfaces, and when 50 a rotating arc or arc-disk is established between such surfaces, it is desirable to be able to regulate the position of the arc at will for

the purpose of insuring equal wear and for producing heat throughout the length of the heating chamber. This I accomplish 55 by an arrangement producing what may be called a "traveling arc." Besides, it is desirable to make the heat uniform at any given time in as long a part of the heating chamber as possible; this I accomplish by 60 what may be called an "oscillating arc," which is an arc made to move automatically to and fro in quick succession.

The invention is illustrated in the accompanying drawings, in which—⁶⁵

Figure 1 is a longitudinal section of the essential elements of the furnace and its circuit connections, the details of construction not being shown; Fig. 2 is a diagram of the furnace with a modified form of rheostat 70 whereby the movements of the arc are caused to be automatic and periodic.

Referring to the drawings, A represents a hollow cylindrical electrode open at its ends to receive and discharge the substance 75 to be treated, and made of carbon. This electrode thus constitutes the heating chamber of the furnace, and is rotatably mounted in an inclined position so that the charge admitted at the upper end from hopper a^1 80 will be equally heated and will steadily travel downward toward the lower end to discharge spout a^2 . The mounting of electrode A may be effected in any suitable manner, such as that shown in Fig. 1, where it 85 will be seen that end collars are provided of which a^3 has a gear engaged by pinion a^4 for rotating the cylinder, and collar a^5 engages supporting rollers a^6 and a^7 , all mounted on any suitable supports. Any 90 gases may escape at hopper a^1 after giving up heat to the fresh incoming charge. The other electrode is shown as a carbon rod B extending longitudinally within electrode A, and having its ends supported in any desired manner. This rod B may have a cylindrical surface, and be centrally located within electrode A, so that the two electrodes will present substantially parallel concentric cylindrical arcing surfaces. Elec- 100 trode A is surrounded by a solenoid a^8 which, when energized, causes the rapid rotation of the arc around the central electrode, producing what may be termed an

arc-disk. The solenoid is connected with the same source of current as that supplying the electrodes.

In order to change the position of the arc and cause the arc to move from end to end of the heating chamber, I connect one pole of the source of current, which may be an alternating current generator G, to both ends of one electrode by branch circuits in which 5 are interposed variable resistances. The other pole of the source of current is similarly connected to the other electrode. Such an arrangement, as shown in Fig. 1, comprises a rheostat R connected at D and E 10 with the ends of electrode B and having its movable contact *r* connected to one pole of the generator. A second rheostat T is connected at F and *f* with the ends of electrode A by brushes *t'* and *t*². The movable contact *t* of this rheostat is connected to the other pole of the generator. The positions 15 of the movable contacts *r* and *t* can be changed at will, but they are usually moved both at the same time in the same direction 20 and proportionately, the position of the arc-disk being thereby regulated so that the latter may be made to travel through the whole tube, to and fro. When the variable point 25 is set so that the current enters mainly on the right-hand side, the arc-disk will move to the left, and vice versa.

In the operation of the furnace, the charge being fed at hopper *a*, the arc is established between the electrodes and is spread into an 30 arc-disk by the action of solenoid *a'*. The position of this arc, or arc disk, within the cylinder depends upon the position of movable contacts *r* and *t*, and hence the relative 35 resistance of the shunt circuits conducting current to the ends of the electrodes. The movements of the arc are due to the tendency of an arc established between parallel electrodes to move away from the end where the current is supplied. When the current 40 is supplied to both ends of the electrodes, the motion of the arc is determined by the variation between the two currents concerned. As the resistances in the branch circuits may 45 be varied, and the currents in said circuits thereby varied, the arc may be shifted. The relation of the resistances is proper when for instance, the added resistance in the circuits connected to the left-hand terminals of the two electrodes, plus the electric resistance 50 of the left-hand parts of the electrodes (reaching from said left-hand terminals to the place where the arc stays, under the given adjustment) is equal to the sum of the two corresponding resistances on the 55 right-hand. It is supposed that the source of current supply for the left-hand terminals and for the right-hand terminals has the same voltage. The same volts applied to resistances which have the same aggregate 60 value produce the same amount of amperes,

that is the left-hand current and the right-hand current (which jointly form the arc) are in this case equal. It has been said above "the motion of the arc is determined by the variation between the two currents concerned." Now, in the case just supposed there is no such variation, and it therefore follows that there is no motion of the arc, that is, the arc remains at a certain place between the electrodes for a given adjustment of the resistances. This is the meaning of the above-mentioned proper relation.

In order to compel the arc to travel rapidly and automatically from end to end of the heating chamber, I provide the arrangement shown in Fig. 2, by which the changes in resistance are rendered periodic and automatic. In that figure, H is a rotating rheostat having a "commutator" *h* connected to one pole of the generator by a contact brush *r'*, while the ends of the rheostat are connected to the ends of electrode B through contact rings D' and E' and the brushes engaging the same. Similarly, the rotating rheostat I having "commutator" *i* engaged by brush *t'*, the latter connected to the other pole of the generator, and contact rings F' and *f*', is similarly connected to electrode A. The rheostats are preferably geared together as shown to secure synchronism. The direct analogy between this arrangement and that shown in Fig. 1 is at once apparent. In the latter case adjustable contacts of the rheostats remain stationary and it is the resistance segments which move.

The resistance of the rheostat may be ten times that of the carbon rod. I may employ alternating currents with the apparatus shown in Fig. 2. The speed of rotation of the rheostats is preferably about twenty revolutions per minute for comparatively low temperatures, and the higher the temperature the higher the speed, within wide limits.

The subject matter of this application for patent is an improvement upon that of my companion application Serial No. 610,286 filed simultaneously herewith, and the generic features common to both applications are not claimed in the present application, but are claimed in the said companion application.

What I claim as new, and desire to secure by Letters Patent of the United States, is—

1. In a device for controlling an electric discharge, the combination of electrodes parallel and opposite to each other, providing between them an air-gap of considerable width, a divided circuit for each of said electrodes, and means to supply the branches of said divided circuit with pulsating currents of substantially one and the same periodicity.

2. In a device for controlling an electric discharge, the combination of parallel electrodes, a divided circuit for said electrodes,

and sources of pulsating currents supplied to the branches of said divided circuit.

3. In a device for controlling an electric discharge, electrodes parallel and opposite to each other, providing between them an air-gap of considerable width, said electrodes being surrounded by solenoid-turns in combination with a divided circuit for said electrodes and with means to supply currents to the branches of said circuit.

4. In an electric furnace, parallel electrodes, a heating chamber surrounded by solenoid-turns and sources of two pulsating currents and electric conductors joining the four ends of said parallel electrodes with said sources and completing a divided circuit.

5. In an electric furnace, parallel electrodes of which the one is surrounded by the other one and solenoid turns surrounding the same, mechanical support of each electrode at both ends, in combination with a divided circuit and a source for supplying differing currents to the electrodes at both ends.

6. In an electric furnace, a pair of concentric cylindrical electrodes and means to rotate the same, in combination with solenoid turns and a divided circuit supplying each end of said pair of electrodes with a pulsating current.

7. In an electric furnace, the combination of two long electrodes parallel and opposite to each other, whereby an air-gap of considerable width is formed between them, mechanical support at both ends of said electrodes, electrical means to cause an arc formed between said electrodes to travel along said electrodes, and other electrical means to cause the arc to move in a direction substantially parallel to the axes of said electrodes.

8. In an electric furnace, the combination of electrodes parallel and opposite to each other, whereby a long air-gap of substantially uniform width is provided between said electrodes, a source of supply of electric current, connections between said source and each end of each of said electrodes, and means for simultaneously varying the amount of current supplied to adjacent ends of said electrodes, whereby an arc formed between said electrodes may be caused to reciprocate along said electrodes.

9. In an electric furnace, the combination of a hollow electrode, an electrode within said first-mentioned electrode, means for supplying electrical energy to said electrodes, and means for alternately varying the energy supplied to adjacent ends of said electrodes.

10. In an electric furnace, the combination of a hollow electrode, an electrode within said first-mentioned electrode, means for

supplying electrical energy to said electrodes, means for alternately varying the energy supplied to adjacent ends of said electrodes, and means for causing the arc to rotate about the inner electrode.

11. In an electric furnace, the combination of a furnace chamber having a hollow cylindrical electrode, an electrode within and concentric to said first-mentioned electrode, a source of electricity, connections to both ends of each of said electrodes, means for periodically varying the amount of current supplied to the ends of said electrodes, and means for rotating said hollow cylindrical electrode.

12. In an electric furnace, the combination of a furnace chamber having a hollow cylindrical electrode, an electrode within and concentric to said first-mentioned electrode, a source of electricity, connections to both ends of each of said electrodes, means for periodically varying the amount of current supplied to the ends of said electrodes, and means for rotating said hollow cylindrical electrode, the axis of said electrodes being inclined to the horizontal.

13. In an electric furnace, the combination of a furnace chamber having a hollow cylindrical electrode, an electrode within and concentric to said first-mentioned electrode, a source of electricity, connections to both ends of each of said electrodes, means for periodically carrying the amount of current supplied to the ends of said electrodes, means for rotating said hollow cylindrical electrode, the axis of said electrodes being inclined to the horizontal, and a solenoid substantially concentric with and surrounding said electrodes.

14. In an electric furnace, the combination of concentric electrodes, forming between them a long air-gap of substantially uniform width, a source of electricity, connections between said source and said electrodes, whereby an arc may be formed between said electrodes, and means to cause said arc to reciprocate along said electrodes.

15. In an electric furnace, the combination of concentric electrodes, forming between them a long air-gap of substantially uniform width, a source of electricity, connections between said source and said electrodes, whereby an arc may be formed between said electrodes, means to cause said arc to reciprocate along said electrodes, and means for causing said arc to rotate about the axis of said electrodes.

16. An electric heating device comprising longitudinally extending adjacent arcing surfaces, and means for so supplying to said surfaces varying electrical energy as to cause the movement of the arc established therebetween.

17. An electric furnace comprising longitudinally extending adjacent arcing sur-

- faces, an electric circuit including said electrodes and a source of electrical energy, and means for varying the energy supplied to opposite ends of said electrodes reciprocally.
- 5 18. An electric furnace comprising longitudinally extending adjacent arcing surfaces, an electric circuit including said electrodes and a source of electrical energy, and means for simultaneously varying the energy supplied to opposite ends of said electrodes reciprocally and periodically.
- 10 19. In an electric furnace, the combination of a hollow electrode, an electrode within the first mentioned electrode, means for supplying electrical energy to said electrodes to form an arc therebetween, means for causing the rotation of the arc about the inner electrode, and means for so varying the energy supplied to said electrodes as to cause the longitudinal travel of the arc.
- 15 20. The process of electric furnace working which consists in causing an arc to reciprocate to-and-fro within a heating chamber, and passing the material to be treated through said heating chamber during the reciprocation of said arc.
- 20 21. The process of electric furnace working which consists in subjecting the material to be treated to the action of a radial arc discharge in a hollow cylindrical heating chamber, and causing the arc discharge to reciprocate to-and-fro within said chamber.
- 25 22. The process of electric furnace working which consists in subjecting the material to be treated to the action of a radial arc discharge in a rotating hollow cylindrical heating chamber, and causing the arc discharge to reciprocate longitudinally in said chamber.
- 30 23. The process of electric furnace working, which consists in subjecting the material to be treated to the action of an arc discharge through the material and between substantially parallel electrodes, and causing the arc discharge to reciprocate to and fro between said electrodes in a direction transverse to the normal travel of the arc.
- 35 24. The process of electric furnace working, which consists in subjecting the material to be treated to the action of an arc discharge between substantially parallel electrodes, and causing the arc discharge to reciprocate to and fro between said electrodes by supplying varying amounts of electricity to both ends of said electrodes.
- 40 25. The process of electric furnace work-
- ing, which consists in forming an arc between substantially parallel electrodes, supplying both ends of said electrodes with electricity, and proportioning the current so supplied according to the position which it is desired the arc shall occupy.
- 45 26. The process of electric furnace working, which consists in passing the material to be treated through a rotatable hollow electrode, and forming in said electrode a diffused electric discharge.
- 50 27. The process of electric furnace working, which consists in passing the material to be treated through a rotatable hollow electrode, forming in said electrode a diffused electric discharge, and causing said discharge to reciprocate to and fro longitudinally of said chamber.
- 55 28. In an electric furnace, the combination of two electrodes, one of said electrodes being a rotatable hollow electrode.
- 60 29. In an electric furnace, the combination of two electrodes, one of said electrodes being a rotatable hollow electrode and the other electrode being located within said hollow electrode.
- 65 30. In an electric furnace, the combination of a rotatable electrode and a second electrode, and means for forming an arc there between.
- 70 31. In an electric furnace, an inclosed heating chamber having a rotating electrode surface therein.
- 75 32. In an electric furnace, the combination of a rotatable hollow electrode forming an inclosed heating chamber, a second electrode therein, means for forming an arc therein, and means for rotating said arc.
- 80 33. In an electric furnace, the combination of a rotatable hollow electrode forming an inclosed heating chamber, a second electrode therein, means for forming an arc therein, and means for diffusing said arc.
- 85 34. In an electric furnace, the combination of an inclosed heating chamber, means for forming a diffused electric discharge therein, and means for causing solid materials to pass in contact with said discharge.
- 90 In testimony whereof, I have signed my name in presence of two witnesses, this twenty-seventh day of October, 1896.
